(57) **CLAIM**

The ornamental design for a container device, as shown and described.

DESCRIPTION

The device relates to a container for holding tablets or the like. The container comprises a hollow body which holds the content, a closure that cooperates with the body to close the container, and a compliance aid device arranged on the container for indicating the time at which the last dose was taken or when the next dose is due.

FIG. 1 is a perspective view of the container device showing our new design;

FIG. 2 is a top plan view thereof;

FIG. 3 is a side view thereof;

FIG. 4 is an opposite side view thereof;

FIG. 5 is a rear elevation view thereof;

FIG. 6 is a front elevation view thereof;

FIG. 7 is a bottom plan view thereof;

FIG. 8 is a perspective view of the second embodiment of the container device;

FIG. 9 is a top plan view thereof;

FIG. 10 is a side view thereof;

FIG. 11 is an opposite side view thereof;

FIG. 12 is a rear elevation view thereof;

FIG. 13 is a front elevation view thereof;

FIG. 14 is a bottom plan view thereof;

FIG. 15 is a perspective view of the third embodiment of the container device;

FIG. 16 is a top plan view thereof;

FIG. 17 is a side view thereof;

FIG. 18 is an opposite side view thereof;

FIG. 19 is a rear elevation view thereof;

FIG. 20 is a front elevation view thereof; and,
